UNITED STATES PATENT OFFICE.

FREDERICK G. WHEELER, OF NEW YORK, N. Y.

SYSTEM OF STREET-CAR PROPULSION.

SPECIFICATION forming part of Reissued Letters Patent No. 11,211, dated December 22, 1891.

Original No. 453,525, dated June 2, 1891. Application for reissue filed September 5, 1891. Serial No. 404,902.

To all whom it may concern:

Be it known that I, FREDERICK G. WHEELER, a citizen of the United States, residing at New York, in the State of New York, have invented 5 a new and useful Improvement in the System of Street-Car Propulsion; and I do hereby declare that the following is a full, clear, and exact description thereof.

My invention relates to improvements in 10 that class of street-car motors in which the water is raised to the requisite heat in a stationary boiler and supplied to a water-chamber on the motor-car, and is an improvement on the system described in the Patent No. 15 299,607, granted to me June 3, 1884.

The invention consists in the particular construction and arrangement of parts, as hereinafter fully described, and pointed out in the claims.

20 Reference is to be had to the accompanying drawings, in which similar letters of reference indicate corresponding parts in all the figures.

Figure 1 is a side elevation of my improvement. Fig. 2 is an end view, partly in section. Fig. 3 is a sectional elevation of the water-chamber and fire-box; and Fig. 4 is a plan view, partly in section, of the lower condenser.

In the drawings, Fig. 1 represents a motor-car, the actuating mechanism of which may be of any suitable construction. To and beneath the lower rear part of the car is secured the water-chamber B. This water-chamber forms a part of and directly communicates 35 with the principal hot-water and steam reservoir of the car, which is to be charged through the intervening water-chamber with hot water from a stationary steam boiler or generator through a pipe b, entering the side of the 40 water-chamber and having a stop-cock b'. The water-chamber surrounds the fire-box, and is preferably formed of an inner and outer shell, the inner shell forming an inner heating-chamber or fire-box b² and the space between 45 the shells forming the water-chamber. The shells of the chamber are provided with doors b³ to permit of charging the chamber from time to time, as required, during the travel of the car, with hot blocks of iron or other suitable or 50 non-inflammable substance capable of receiving and maintaining a high degree of heat, and which will serve to maintain the temperature

of the previously-charged hot water. From the hot-water chamber B lead pipes c, which connect the water-chamber with the lower pipes 55 or tubes C of the series of circulating pipes or tubes C, D, E, and F, which are connected by couplings d, e, and f. Above the series of pipes or tubes is arranged the dome G, which forms a part of the circulating system, and 60 with which the upper pipes F are connected by the coupling g. From the lower side of the dome G lead pipes h, which extend to and connect the said dome with the water-chamber. By means of the pipes c and h the water-chamber is connected to each end of the tube system through the dome, thus affording a complete circulation of the water. To accelerate 65 the circulation of water the water-chamber is also connected to the dome G by means of pipe i, which, passing from the top of the water-chamber, as shown, directs any accumulation 70 of steam in the water-chamber to the current of circulation in the dome G. From the top of the dome G leads a pipe k, which is connected 75 to the pipes k', leading to the cylinders H, and through which steam is supplied to said cylinders.

Under the front part of the car are mounted two condensers I I', one for each cylinder, and 80 into which the exhaust-steam from the adjoining engine-cylinder passes through the passages l. The condensers I are preferably mounted on the car, so as to be in about the same horizontal plane or below the engine-cylinder, as clearly shown in the drawings. The condensers consist of boxes or casings having inclined bottoms and provided with a series of longitudinal tubes m, extending through them, the said tubes having both 85 ends open and being preferably of copper or some highly-sensitive metal, the outer ends of which are formed in a bell or funnel shape, so that upon the movement of the car the outer area of the flaring ends of the tubes, 90 upon which the air will impinge, will largely exceed that of the tube itself and will concentrate all the air striking the outer surface of the exhaust-chamber into the tubes. The condensers are in communication with each 95 other at their rear lower ends, and are so arranged that the tubes will be in the direction of line of movement of the car, so that as the car moves in either direction the air will be 100

drawn through the tubes by suction and the exhaust-steam rapidly condensed. To facilitate the condensation of the steam I arrange above the system of circulating-pipes an auxiliary condenser J, constructed in a similar manner to the condensers II', and connected thereto by branch pipes n and n', so that any portion of the exhaust-steam in the condensers I remaining uncondensed will rise to the upper condenser J and there be condensed and returned to the condensers I I'.

In order that the water of condensation in the condensers I I' may be returned to the water-chamber B, and thereby produce a complete circulating system, I mount a pump K on the car and connect it with the condenser I by the pipe o and with the water-chamber B by the pipe p. The pump K is operated by an eccentric q on one of the axles of the car, connected to a lever r, which in turn is connected to the pump.

The operation is as follows: Hot water having been supplied to the water-chamber B and a very high temperature being maintained by means of hot bars of iron or other suitable or non-inflammable substance, the water will be caused to pass through the various pipes and then back again to the water-chamber, a continuous circulation of heated water being thus maintained. The steam generated will accumulate in the dome G and will pass through the pipes k k' to the cylinders H. The exhaust-steam from the cylinders will pass into the condensers I I' J, there condensed, and the water of condensation conducted from the lowest point in condensers I I' back to the water-chamber by the pump K.

From the above-described construction and arrangement of parts I cause the water to circulate through the series of tubes back to the water-chamber and also cause the water of condensation from the exhaust-steam to be led back to the said water-chamber, thereby producing a complete circulating system.

Although I have shown two condensers I I', one for each cylinder, yet one could be made

to serve for both cylinders and the upper condenser J could be dispensed with, or two upper condensers could be used, if desired; but I prefer to use the three condensers, as shown. 50

Having now described my invention, what I claim as new, and desire to secure by Letters Patent, is—

1. In a system of street-car propulsion, the combination, with the engine-cylinders, of a 55 water-chamber, a system of circulating-pipes connected with the cylinders and water-chamber, condensers arranged in the front lower part of the engine and connected with the exhaust-ports of the cylinders, an auxiliary condenser arranged above the level of the first-named condensers and connected with the same, and a pump connected with the lower condensers and the water-chamber, substantially as described. 60

2. In a system of street-car propulsion, the combination, with the engine-cylinder, of the water-chamber surrounding an inner heating-chamber, a system of pipes connecting the water-box and cylinders, the condensers I I' 70 J, connected together, and the condensers II', connected to the exhaust-ports of the engine-cylinders, the pump K, connected to the condensers I I' and water-chamber B, and means for operating the pump from the axle of the 75 motor, substantially as described.

3. In a motor, and in combination, a firebox, a water-chamber in contact therewith, a reservoir composed of a series or system of tubes, an engine-cylinder, connections between the reservoir and the engine-cylinder, a condenser connected with the exhaust, and means interposed between the condenser and the water-chamber for conducting the water of condensation back to the said water-chamber, substantially as described. 85

This specification signed and witnessed this 12th day of August, 1891.

FREDERICK G. WHEELER.
